UNITED STATES PATENT OFFICE.

CHARLES C. BARGREEN, OF STREATOR, ILLINOIS.

DESIGN FOR A WATER-COOLER.

48,360.

Specification for Design.

Patented Jan. 4, 1916.

Application filed September 24, 1915. Serial No. 52,532. Term of patent 7 years.

To all whom it may concern:

Be it known that I, CHARLES C. BARGREEN, a citizen of the United States, residing at Streator, in the county of La Salle and State of Illinois, have invented a new, original, and ornamental Design for a Water-Cooler, of which the following is a specification, reference being had to the accompanying drawing, forming part thereof.

The drawing presents the water cooler in perspective, showing my new design.

I claim:

The ornamental design for a water cooler as shown.

In witness whereof, I have hereunto subscribed my name this 20th day of September, 1915.

CHARLES C. BARGREEN.
